(57) **CLAIM**

The ornamental design for a display screen with graphical user interface, as shown and described.

DESCRIPTION

FIG. 1 is a front view of a display screen with graphical user interface, showing our new design;

FIG. 2 is a second embodiment thereof; and

FIG. 3 is a third embodiment thereof.

FIG. 4 is a front view of a fourth embodiment of a display screen with graphical user interface, showing our new design;

FIG. 5 is a front view of a fifth embodiment of a display screen with graphical user interface, showing our new design;

FIG. 6 is a front view of a sixth embodiment of a display screen with graphical user interface, showing our new design;

FIG. 7 is a front view of a seventh embodiment of a display screen with graphical user interface, showing our new design; and,

FIG. 8 is a front view of an eighth embodiment of a display screen with graphical user interface, showing our new design.

The broken lines showing a display screen and elements of the graphical user interface illustrate portions of the article, and form no part of the claimed design.

It is certified that error appears in the above-identified patent and that said Letters Patent is hereby corrected as shown below:

In the Specification

In the Description, delete:

“FIG. 4 is a front view of a fourth embodiment of a display screen with graphical user interface, showing our new design;

FIG. 5 is a front view of a fifth embodiment of a display screen with graphical user interface, showing our new design;

FIG. 6 is a front view of a sixth embodiment of a display screen with graphical user interface, showing our new design;

FIG. 7 is a front view of a seventh embodiment of a display screen with graphical user interface, showing our new design; and,

FIG. 8 is a front view of an eighth embodiment of a display screen with graphical user interface, showing our new design.”

Signed and Sealed this
Thirtieth Day of August, 2022
